ATTORNEYS

DRILL BIT WITH STAGGERED TEETH

BACKGROUND OF THE INVENTION

1. Field of The Invention

The present invention relates generally to percussion drilling, as in rotary air hammer drilling and in cable drop drilling, and more particularly to a novel drill bit incorporating opposing teeth which are staggered vertically or are set at or are of different drilling heights, that is, one tooth extends outwardly from the end of the bit further than the other.

2. Description of the Prior Art

As is stated in applicant's copending U.S. Pat. application Ser. No. 661,560, filed Aug. 18, 1967, there has long existed the need for a percussion drill bit which will reduce materially the recrushing of rock material previously cut and which will materially increase the inches per hour drilled over standard equipment. In the applicant's wide knowledge, the art is lacking a solution of this need, except for the applicant's contribution incorporated in his novel expandable drill bit as shown in his said copending application. The present novel drill bit including staggered teeth in the sense defined above is a further improved solution to the need.

Additionally, the drilling art has long sought a solution to carbide insert breakage in percussion drilling. The present improvement provides such sought solution.

SUMMARY OF THE INVENTION

Broadly, a preferred embodiment of the present novel percussion drill bit includes a streamlined shaft or housing supporting two spaced opposed blocklike teeth at the lower end, which may be of the expandable type as illustrated in the drawings. Each tooth includes an elongated cutter insert of carbide or other suitable material. The teeth may be of tool steel. One tooth extends outwardly from the end of the bit further than the other, hence, is of greater drilling height, or has such greater effective drilling height, than the other, which increases the cutting effect of the bit by increasing the unit load and, consequently, the cutting rate per hour of the drill. This novel arrangement also substantially eliminates pinching by carbide inserts, hence, reduces breakage to a nominal percentage by drilling an oversized hole allowing the remaining or opposing carbide to be free from pinching and breakage that could occur in a tight hole. The staggered principle causes a larger hole diameter to be drilled as the lead tooth "kicks" outwardly upon impact with hole bottom. This larger diameter hole prevents the two opposing carbides from "pinching" in a tight hole. The high unit load created by one carbide, rather than two, results in faster drilling.

Thus, an object of the present invention is to provide a novel drill bit which is constructed to increase the cutting effect thereof over other bits, hence, to increase the drilling rate per hour of the drill of which it forms a part.

Other objects are to provide a novel drill bit which reduces carbide insert breakage to a nominal percentage, which is highly effective, which is adapted to function at its increased drilling rate for extended intervals, which is of sturdy construction, which is adapted to multidrilling usage, and which otherwise fulfills the objects and advantages sought therefor.

BRIEF DESCRIPTION OF THE DRAWINGS

FIG. 1 is a side elevational view of a preferred drill bit incorporating the teachings of the present invention;

FIG. 2 is an enlarged fragmentary front elevational view of the lower end of the bit of FIG. 1;

FIG. 3 is a view similar to FIG. 2 rotated through 90°;

FIG. 4 is a bottom plane view of FIG. 2; and

FIG. 5 is a vertical cross-sectional view on substantially the line 5-5 of FIG. 3.

DESCRIPTION OF PREFERRED EMBODIMENT

Referring to the drawings more particularly by reference numerals, 10 indicates generally a cable percussion drill bit

constructed to include the principles of the present invention. The bit 10 includes a shaft 12 having a threaded, reduced upper end 14 and a lower end 16 having two cavities or chambers 18 open at the ends and bottom and separated by a depending partition or wall 20.

10 A tooth 22 of block form including a round hole 24 with an enlarged leading portion 26 and having an insert 28 of carbide or other suitable material and of the configuration shown in the drawings is mounted in one cavity 18. A second tooth 30 extending a lesser distance outwardly from the end of the bit, hence, of shorter drilling height than the tooth 22, but otherwise the same except for a threaded hole 32 instead of the hole 24 is mounted in the other cavity 18. Successful experimental teeth 22 have ranged from one-eighth inch to one-half inch greater in drilling height as defined above than associated teeth 30. With much less the carbides tend to stick and with much more the crushing effect of tooth 30 diminishes sharply. The teeth 22 and 30 can be of the same height, of course, with the former shimmed or otherwise positioned to extend below the latter to attain a greater effective drilling height. The teeth 22 and 30 may be of solid good tool steel. The tooth 30 will crush cut rock. A heavy bolt 34 with a head 36 extends through the hole 24, a hole 38 in the partition 20, and 15 threadedly engages the hole 32 to maintain the teeth 22 and 30 in operative positions. The hole 38 is a little larger than the diameter of the bolt 34 to prevent undue impact on or contact with the bolt 34 in drilling to prevent stressing or binding of the bolt 34. It is understood that variations may be made in the 20 securing means.

25 A shim 40 of metal or other suitable material is shown between each of the teeth 22 and 30 and the partition 20 to maintain the proper drilling positions of the teeth 22 and 30. It will be understood that more shims 40 will be added as the 30 teeth wear in drilling.

35 It will be further understood that the novel aspect of the present improvement of incorporating teeth of selected different drilling heights or positions extending different distances from the end of the bit may be incorporated in stationary teeth as well as adjustable teeth. Additionally, it may be included in percussion and other drill bits having more than 40 two drill teeth, as three or four. For greatest effectiveness in a four-tooth bit, for example, the teeth should be in the form of an "X" and not at 90°. The present novel drill bit is highly effective in achieving the sought objectives. Faster trouble free drilling under comparable conditions are attained than with other bits.

45 It is apparent that there has been provided a drilling bit which fulfills the objects and advantages sought therefor.

50 It is to be understood that the foregoing description and the accompanying drawing have been given by way of illustration and example. It is also to be understood that changes in form of the elements, rearrangement of parts, and substitution of equivalent elements, which will be obvious to those skilled in the art, are contemplated as within the scope of the present invention which is limited only by the claims which follow.

I claim:

55 1. A percussion drill bit including a main body, at least two active drill teeth secured in said main body, one drilling tooth extending a greater distance outwardly from the end of the bit than the other and being of greater drilling effectiveness than the other, said one drilling tooth being the primary drilling element and effective determinant of hole cross section, the 60 other of said at least two active drill teeth being a secondary drilling element operating within the hole cross section basically determined by said one drilling tooth.

65 2. The drill bit of claim 1 in which two teeth including said one drill tooth of greater effectiveness drilling are on a substantially diagonal line across the bit.

70 3. The drill bit of claim 2 in which at least the tooth of greater effectiveness drilling and another tooth are at the outer ends of the diagonal line.

75 4. The drill bit of claim 1 in which at least the tooth of greater effectiveness drilling has a carbide drilling insert.

5. The drill bit of claim 2 in which at least the tooth of greater effectiveness drilling has a carbide drilling insert.
6. The drill of claim 1 in which said teeth are adjustable.
7. The drill of claim 1 in which the said one drill tooth extends outwardly from the end of the bit substantially one-

8. eighth inch more than the other.

9. The drill of claim 1 in which said one drill tooth extends outwardly from the end of the bit between substantially one-eighth and one-half inch more than the others.
